COLLAPSIBLE SHELTER

Gene F. Dabney, Los Angeles, Calif.

Application December 22, 1939, Serial No. 310,532

2 Claims. (Cl. 135—5)

This invention relates to shelters and more especially to a collapsible sun shelter, and is a continuation in part of my copending application, Serial No. 210,761, filed May 28, 1938.

An object of the invention is to provide a simple, practical and inexpensive article of the character described.

Another object is to provide a sun and wind shelter having novel features of collapsibility and portability.

Another object is to provide in a shelter of the character described improved features of comfort, facility and simplicity of erection and collapsibility.

More specific objects and advantages will appear and be brought out more fully in the following specification, reference being had to the accompanying drawings, wherein:

Fig. 1 is a view of an embodiment of the invention showing the article fully expanded in condition for use;

Fig. 2 is a view of the same collapsed and compacted for transporting;

Fig. 3 is a side view of one of the brace members;

Fig. 4 is a sectional view taken along the line 4—4 of Fig. 3;

Fig. 5 is a fragmentary sectional view illustrating one of the said structural features;

Fig. 6 is a fragmentary sectional view showing another of the structural features;

Fig. 7 is a view showing means for securing the article to the ground;

Fig. 8 is a perspective view of a modified form of the invention;

Fig. 9 is a vertical section;

Fig. 10 is a plane view partly in section of the same;

Fig. 11 is a fragmentary detail of the cover showing means for fastening the cover member to the floor member;

Fig. 12 is a fragmentary view illustrating the means of fastening the device in folded position;

Fig. 13 is a fragmentary sectional view taken along the line 13—13 of Fig. 10;

Fig. 14 is a sectional view taken along the line 14—14 of Fig. 15; and

Fig. 15 is an end elevation of the hub also shown in Fig. 14.

Referring more particularly to the drawings, I show a pair of bow members 10 and 11 respectively, preferably of resilient steel or the equivalent, and a plurality of similar bow members 12 positioned therebetween, the bow members each

having terminal loops 13 by which they are secured to rings 14. A cover 15 of fabric or the like is secured to bows 10, 11 and 12 in any suitable manner, the front free edge 16 of which 5 may be scalloped or given any desired configuration.

A pair of floor piece 17 are secured to rear or bottom bow 11 and may have their overlapping edge portions 18 secured together by buttons or 10 snap fasteners 19 or the like. An anchoring stake 20 is provided for each ring 14 and is preferably constructed of twisted steel wire having an elongated loop 21 for connection with each ring 14 and may be provided with a loop 22 to facilitate placing in the ground and removal therefrom.

A pair of braces 23 are pivotally secured at 24 and 25 respectively to bows 10 and 11 and each brace consists of a pair of strap irons 26 pivoted together at 27 and provided with a rectangular collar 28 which may be slipped over the overlapping portions of members 26 to maintain them in straight relation for bracing and which may be slipped away from the overlapping portions

25 for collapsing the brace in the usual manner. A central brace 29 is provided for the article and comprises strap members 30, 31 and 32; member 31 being pivoted at 33 to bow 11; member 32 being pivotally secured to members 30 and 31 in a manner similar to braces 26; member 30 having an L-shaped member 34 secured adjacent the

30 free end thereof whereby the same may be engaged with bow 10 as shown in Fig. 5 when the brace 29 is extended and stiffened as shown 35 in Fig. 1.

A plurality of rings 14a similar to ring 14 may be secured to tabs 14b, the latter being sewed to cover 15 adjacent bow 11 for auxiliary anchoring as shown in Fig. 6. A plurality of ties 34 are

40 secured to floor pieces 17 for securing the article in collapsed position as shown in Fig. 2. A bail 35 is secured from detachment by a strap 36 secured to one of the floor pieces 17, the ends of which are adapted to engage apertures in strap members 30 and 32 whereby the article may be carried when compacted.

I show a plurality of pockets 37 secured on the inner side of cover 15 which may be used for placing therein articles such as cigarettes, magazines 50 and the like.

The article may be compacted by withdrawing the stakes 20 from the ground, removing member 34 from bow 10 and folding brace 29 and braces 23, thus permitting the bows 10 and 12 to collapse on bow 11. Floor pieces 17 may thereupon

be wrapped around the bows and cover 15 and the end portions overlapped as shown in Fig. 2 and passed between braces 30 and 32 and tied by ties 34 and bail 35 secured to braces 30 and 31.

In Figs. 8 to 15 I show a modified form of a shelter 40 in which a pair of hubs 41 each having an aperture 42 secure the ends of a plurality of resilient wire ribs 43 having end portions 44 turned inwardly at substantially right angles which extend through apertures 45 in one of the hub member plates, of which there are two, they being held together by a plurality of bolts 46. Centrally at the rear portion of the shelter a U-shaped clip 47 is secured about the terminal rib 43 and held by bolt 48. A strap 49 is secured by a bolt or rivet 50 to clip 47 and is secured to a ring 51 which is adapted to engage the head of a pin 52 secured to a U-shaped clip 53 secured to the other terminal rib 43 by bolt 54.

A floor piece 55 of suitable fabric material, such as canvas or the like, is provided with a plurality of apertures having eyelets 56 secured thereto and a ring 57 is secured as by a strap 58 to the lower terminal rib 43 adjacent each eyelet 56 for the reception of a bifurcated peg 59 having a shouldered head by which the floor 55 is held to the ground, a peg passing through each ring 57.

The fabric cover portion comprises a plurality of segments 60 which overlap at their edge portions which are sewed or otherwise secured together as at 61, a rib 43 being held in each of the overlapping portions. An abbreviated apron 62 may be secured to the forward terminal rib portion if desired. A rear edge portion 63 of the top may be divided and left free so as to overlie the rear edge portion of the flooring 55. If desired, these parts may be secured together in any suitable manner.

A collapsible stiffener strap is provided and comprises members 64, 65 and 66, members 64 and 65 being secured together by any suitable pivot 67 and members 64 and 66 being similarly secured by a pivot 67. These members each consist preferably of a resilient steel bar section and

are provided with interfitting humps and recesses 68 and 69 by which the stiffener strap will be held in extended position against inadvertent collapse, but may be collapsed by pivoting the members 64, 65 and 66 on their pivots 67 when the shelter is to be collapsed. Member 65 is pivotally secured to bolt 48 by the head 10 thereof, and member 66 is similarly pivotally secured to bolt 54 by the head 11 thereof. One or more pockets 72 may be provided on the inner side of the cover element if desired.

As may be seen in Fig. 12, when the shelter is collapsed pin 52 of clip 53 is adjacent strap 49 and ring 51 secured to clip 47 and ring 51 may be secured to pin 52 and the shelter secured in collapsed position, the flooring 55 being rolled or folded within the folds of the cover material.

Having described my invention, what I claim is:

1. In a device of the character described, the combination of a pair of hub members, two terminal rib members and a plurality of intermediate rib members, each said rib member being individually pivoted at each of its ends to one of the hub members whereby said ribs can be folded together or swung apart to form a frame simulating a section of a sphere, a cover secured at spaced intervals to each of said ribs and foldable with them, and means engageable with the terminal ribs when they are swung apart for holding the frame unfolded and the cover taut, said last named means comprising a semi-rigid strap member composed of a plurality of sections pivotally connected with each other at their ends so that they can be collapsed to lie face to face or extended in longitudinal alignment for the frame holding purpose, said strap member being permanently secured at one end to one terminal rib and detachably connectable with the other terminal rib.
2. A structure as defined in claim 1 in which means is provided on said strap and effective at the pivotal connections therein to hold the strap sections in longitudinal alignment and against inadvertent folding movement.

GENE F. DABNEY.
